ABSTRACT OF THE DISCLOSURE

Turbine bucket profiles for the transonic fluid flow region at the outer portions of axial flow steam turbine buckets, the profiles being characterized by substantially flat pressure and suction sides diverging toward the trailing edge over the mid-portion of the profile, the buckets overlapping one another and shaped to provide a transonic and supersonic flow region between buckets.

BACKGROUND OF THE INVENTION

This invention relates to axial flow steam turbine bucket design for high speed, long buckets wherein the fluid flow conditions at the radially outer portions, especially of the last stage buckets, exceeds the speed of sound. Such buckets are known as transonic buckets because the steam enters at a speed less than that of sound and emerges at supersonic speeds.

Transition from subsonic to supersonic conditions without the loss of efficiency represents a difficult aerodynamic design problem. That which would give a theoretical optimum flow condition is often impossible to achieve in a practical blade due to thinness of the blade sections near the outer tips of the buckets. Efforts to achieve good transonic profiles are known in the prior art, wherein a conventional subsonic bucket profile (concave on the pressure side and convex on the suction side) has been reversed so that there is a slightly convex curve on the pressure side and slightly concave curve on the suction side. These profiles and a history of the prior art are exemplified in U.S. Pat. 3,333,817 issued to F. Rhomberg on Aug. 1, 1967. Such prior art blade profiles terminate in a relatively thick trailing edge which is disposed opposite a blunt leading edge of the adjacent blade.

Accordingly, one object of the present invention is to provide an improved transonic bucket profile which gives improved efficiency in the transition from subsonic to supersonic flow between buckets.

Another object of the invention is to provide an improved transonic bucket profile which is of more uniform thickness throughout so as to add strength without sacrifice in aerodynamic design.

DRAWING

The single figure of the drawing is a developed view of two adjacent blade cross sections taken near the outer tips of the buckets and looking radially inward.

SUMMARY OF THE INVENTION

Briefly stated, the invention is practiced by arranging adjacent blades so that the blade sections near the outer periphery overlap about $\frac{1}{4}$ of the total chord length and shaping the blade profiles a convergent-divergent nozzle over the overlapped one-quarter. Each blade profile is characterized by two locations of increased blade thickness, one near the nose and one near the tail section. Over the midsection of the blade profile, the pressure side and suction side are substantially flat and diverge from one another toward the tail section.

2

DESCRIPTION OF THE PREFERRED EMBODIMENT

Referring now to the drawing, there is shown a cross section of two adjacent buckets, designated 1 and 2, taken near the bucket outer tips. It will be understood by those skilled in the art that the configuration and orientation near the radially inner ends of these same buckets will be quite different in appearance and that there is a gradual transition toward the profiles indicated in the drawing. Each bucket profile, such as 2, is divided for the purpose of definition herein into a nose section 3 extending about $\frac{1}{4}$ of the chord length, a mid-section 4 extending about $\frac{1}{2}$ of the chord length, and a tail section 5 extending the remaining $\frac{1}{4}$ of the chord length. The nose section 3 of one blade overlaps and is roughly coextensive with the tail section 5 of an adjacent bucket.

In the drawing, the blades travel in the direction indicated by the arrow. The upper side 6 is the pressure side of the blades while the lower side 7 is the suction side.

In the nose section 3, the point of greatest blade thickness is indicated at d and is located back from the leading edge 8 by distance l . The contour of the blade profile on both pressure and suction side over the distance l is quasi-elliptical and has an l/d ratio satisfying the condition:

$$l/d \geq 1.8$$

From the point of greatest thickness d , the blade narrows toward a neck 11 at the start of the mid-section 4 of the blade. The suction side in this narrowing cross section is gently concave as indicated at 12.

Over the mid-section 4 of the blade, the pressure side and suction side are substantially flat. It is to be particularly noted also that the flat pressure and suction sides diverge from the relatively narrow neck 11 at the beginning of mid-section 4 to a relatively thick "throat" portion indicated at its thickest point as t . Throat portion t is located approximately $\frac{3}{4}$ of the chord length along the blade and is so designated because it lies opposite the thickest nose section d to form therewith the throat of a convergent-divergent nozzle between blades 1, 2.

In some cases, the nose thickness d will be slightly greater than t and in other cases the throat thickness t will be slightly greater than d . In either event, however, the two are approximately the same, relative to other parts of the blade.

The tail section 5 of the blade profile comprises a relatively flat suction side which is a continuation of the aforementioned flat suction side over the mid-section of the blade. On the pressure side, the blade curvature is reversed after passing through the throat portion t and caused to curve gently toward the trailing edge 9 to provide a slightly concave surface on the pressure side. The radius of curvature over this portion, designated 10, should be at least 20 times that of the radius of curvature at the throat section t .

OPERATION

The operation of the invention is as follows. At the location of the blade profiles 1 and 2 near the outer blade portions, the thickest nose portion d of blade 2 is disposed opposite the thickest throat portion t of blade 1 and the two together form a convergent-divergent nozzle of transonic flow conditions indicated at I between the dashed lines. Adjacent zone I is a zone II of supersonic flow and zone III of supersonic flow at essentially constant velocity. The radius of curvature of the concave suction side 12 of blade 2 and the radius of curvature of the concave pressure side 10 of blade 1 are both calculated, preferably using the "method of characteristics," which is well known to those skilled in the art, to provide optimum flow conditions.

One advantage of the foregoing design, in having a nose section and a tail section which are substantially the same thickness, is to provide a more symmetrical bucket of greater strength and to allow enough material for shielding against erosion on leading edge at the outer tips. Also, by employing flat profiles over approximately half of the pressure side and approximately $\frac{3}{4}$ of the suction side, simplifications as to blade shaping are introduced.

Well controlled transition from a transonic flow to a supersonic flow in a compressed region between overlapped buckets, such that the static pressures along suction and pressure side of section 5 are converging gradually to the downstream static pressure, adds greatly to the overall efficiency of the transonic bucket described in relation to previously known designs.

While there is shown what is considered at present to be the preferred embodiment of the invention, it is of course understood that various other modifications may be made therein, and it is intended to cover in the appended claims all such modifications as fall within the true spirit and scope of the invention.

What we claim as new and desire to secure by Letters Patent of the United States is:

1. In an axial flow turbine having buckets with tips thereon traveling with respect to elastic fluid passing therethrough under transonic conditions, each of said bucket outer portions being shaped to define a blade profile having a rounded nose section, a mid-section and a tail section extending over approximately the first quarter, the middle half and the last quarter of the chord length respectively,

said nose section increasing and then decreasing in thickness to provide a first reference point of maximum thickness therein,

said mid-section having substantially flat sides increasing in thickness throughout its length to provide a second reference point of maximum thickness between the mid-section and tail section, said first and second reference points being of approximately the same blade thickness.

2. In an axial flow turbine having buckets with tips thereon traveling with respect to elastic fluid passing therethrough under transonic and supersonic flow conditions, each of said bucket outer portions being shaped to define a blade profile having a rounded nose section ex-

tending over approximately one-quarter of the chord length, a mid-section extending over approximately one-half of the chord length, and a tail section extending the remaining one-quarter of the chord length,

5 said nose section disposed in overlapping and coextensive relationship with the tail section of an adjacent blade profile,

said nose section gradually increasing in thickness commencing at the leading edge thereof and then decreasing in thickness,

10 said mid-section defining substantially flat surfaces on the pressure and suction sides of the profile and also diverging slightly toward the tail section,

15 said tail section having a substantially flat suction side which is a continuation of said mid-section suction side and having a surface on the pressure side which gently converges from a maximum throat thickness to the bucket trailing edge.

3. The combination according to claim 2, wherein the 20 contour of the nose section from the leading edge to the thickest nose portion is quasi-elliptical and substantially symmetrical on the pressure and suction sides.

4. The combination according to claim 2, where the 25 maximum thickness of the blade in the nose section and the maximum thickness of the blade at the commencement of the tail section are substantially the same.

5. The combination according to claim 2, wherein the 30 surface of the suction side of the nose section of one blade and the surface of the pressure side of the tail section of an adjacent blade are disposed opposite one another and are slightly concave and shaped to obtain a confined supersonic flow region between blades.
